Des. 240,269
Patented June 8, 1976

240,269

COMBINED BINOCULAR AND COMPASS

Nils Viktor Johansson, 123 Maltesholmsvägen,
162 37 Vällingby, Sweden

Filed Mar. 21, 1975, Ser. No. 568,699

Term of patent 7 years

Int. Cl. D16—06

U.S. CL. D16—99

FIG. 1

FIG. 2

FIG. 3

FIG. 4

FIG. 5

FIG. 6

FIG. 1 is a perspective view of a combined binocular and compass showing my new design;

FIG. 2 is a top plan view thereof, with the compass optical inlet in a closed position;

FIG. 3 is a front elevation thereof;

FIG. 4 is a side elevation thereof;

FIG. 5 is a bottom plan view thereof; and

FIG. 6 is a rear elevation thereof.

I claim:

The ornamental design for a combined binocular and compass, as shown and described.
